(57) **CLAIM**

The ornamental design for a conduit layout tool or portion thereof, as shown and described.

DESCRIPTION

FIG. 1 is a top perspective view of a conduit layout tool in accordance with another embodiment of the present design; FIG. 2 is a left side elevation view of the conduit layout tool of FIG. 1; FIG. 3 is a right side elevation view of the conduit layout tool of FIG. 1;

FIG. 4 is a top plan view of the conduit layout tool of FIG. 1;

FIG. 5 is a bottom plan view of the conduit layout tool of FIG. 1;

FIG. 6 is a top elevation view of the conduit layout tool of FIG. 1;

FIG. 7 is a bottom elevation view of the conduit layout tool of FIG. 1;

FIG. 8 is a top perspective view of a conduit layout tool in accordance with another embodiment of the present design; FIG. 9 is a left side elevation view of the conduit layout tool of FIG. 8;

FIG. 10 is a right side elevation view of the conduit layout tool of FIG. 8;

FIG. 11 is a top plan view of the conduit layout tool of FIG. 8;

FIG. 12 is a bottom plan view of the conduit layout tool of FIG. 8;

FIG. 13 is a top elevation view of the conduit layout tool of FIG. 8;

FIG. 14 is a bottom elevation view of the conduit layout tool of FIG. 8;

FIG. 15 is a top perspective view of a conduit layout tool in accordance with another embodiment of the present design; FIG. 16 is a left side elevation view of the conduit layout tool of FIG. 15;

FIG. 17 is a right side elevation view of the conduit layout tool of FIG. 15;

FIG. 18 is a top plan view of the conduit layout tool of FIG. 15;

FIG. 19 is a bottom plan view of the conduit layout tool of FIG. 15;

FIG. 20 is a top elevation view of the conduit layout tool of FIG. 15;

FIG. 21 is a bottom elevation view of the conduit layout tool of FIG. 15;

FIG. 22 is a top perspective view of a conduit layout tool in accordance with another embodiment of the present design; FIG. 23 is a left side elevation view of the conduit layout tool of FIG. 22;

FIG. 24 is a right side elevation view of the conduit layout tool of FIG. 22;

(Continued)

FIG. 25 is a top plan view of the conduit layout tool of FIG. 22;
 FIG. 26 is a bottom plan view of the conduit layout tool of FIG. 22;
 FIG. 27 is a top elevation view of the conduit layout tool of FIG. 22;
 FIG. 28 is a bottom elevation view of the conduit layout tool of FIG. 22;
 FIG. 29 is a top perspective view of a conduit layout tool in accordance with another embodiment of the present design;
 FIG. 30 is a left side elevation view of the conduit layout tool of FIG. 29;
 FIG. 31 is a right side elevation view of the conduit layout tool of FIG. 29;
 FIG. 32 is a top plan view of the conduit layout tool of FIG. 29;
 FIG. 33 is a bottom plan view of the conduit layout tool of FIG. 29;
 FIG. 34 is a top elevation view of the conduit layout tool of FIG. 29;
 FIG. 35 is a bottom elevation view of the conduit layout tool of FIG. 29;
 FIG. 36 is a top perspective view of a conduit layout tool in accordance with another embodiment of the present design;
 FIG. 37 is a left side elevation view of the conduit layout tool of FIG. 36;
 FIG. 38 is a right side elevation view of the conduit layout tool of FIG. 36;
 FIG. 39 is a top plan view of the conduit layout tool of FIG. 36;
 FIG. 40 is a bottom plan view of the conduit layout tool of FIG. 36;
 FIG. 41 is a top elevation view of the conduit layout tool of FIG. 36;
 FIG. 42 is a bottom elevation view of the conduit layout tool of FIG. 36;
 FIG. 43 is a top perspective view of a conduit layout tool in accordance with another embodiment of the present design;
 FIG. 44 is a left side elevation view of the conduit layout tool of FIG. 43;

FIG. 45 is a right side elevation view of the conduit layout tool of FIG. 43;
 FIG. 46 is a top plan view of the conduit layout tool of FIG. 43;
 FIG. 47 is a bottom plan view of the conduit layout tool of FIG. 43;
 FIG. 48 is a top elevation view of the conduit layout tool of FIG. 43; and,
 FIG. 49 is a bottom elevation view of the conduit layout tool of FIG. 43;
 The features shown in broken lines in the various figures form no part of the claimed design. The shading shows contours and surfaces of the present invention.
